UNITED STATES PATENT OFFICE

134,395

DESIGN FOR TUBE SHEARS

Carl C. Bain, Oakmont, Pa., assignor to Mine Safety Appliances Company, Pittsburgh, Pa.

Application March 10, 1942, Serial No. 106,129

Term of patent 14 years

To all whom it may concern:

Be it known that I, Carl C. Bain, citizen of the United States, residing at Oakmont, in the county of Allegheny and State of Pennsylvania, have invented a new, original, and ornamental Design for Tube Shears, of which the following is a specification, reference being had to the accompanying drawing, forming a part thereof.

Fig. 1 is an end elevational view of the tube shears incorporating my new design;

Fig. 2 is a plan view thereof;
Fig. 3 is a side elevational view thereof;
Fig. 4 is another end view thereof; and
Fig. 5 is a plan view illustrating an operative position of the shears.

I claim:

The ornamental design for tube shears, substantially as shown.

CARL C. BAIN.
